UNITED STATES PATENT OFFICE.

HUGO BERGQUIST, OF SWISSVALE, AND PAUL T. KEEBLER, OF JEANNETTE, PENNSYLVANIA, ASSIGNORS TO ELLIOTT COMPANY, OF PITTSBURGH, PENNSYLVANIA, A CORPORATION OF PENNSYLVANIA.

HEAT EXCHANGER.

Application filed February 16, 1928. Serial No. 254,692.

The present invention relates broadly to the art of heat exchangers, and more particularly to an improved construction adapted for use in heaters of the indirect type as commonly utilized for the interchange of heat between a vapor and a liquid. The utility of the invention is not limited to an operation in which the vapor is used entirely as a heating means for the liquid, advantageous results being obtained in case of a reverse operation in which the primary object of the apparatus is to utilize liquid for condensing the vapor.

For purposes of explanation of the present invention, it will be herein described in connection with a water heater in which the water passes through the tubes and the vapor passes around the tubes. In apparatus of this type as ordinarily constructed, it is customary to provide the necessary reinforcement for the tube sheet by means of one or more staybolts extending through the tube sheet, the water space in the water head, and the water head itself, and effective in tension. Such staybolts have many inherent disadvantages, which it is partly the object of the present invention to obviate. In the first place, a staybolt structure requires a water head of special design in order to afford sufficient strength to satisfactorily carry its own load and the load on the tube sheet. It also necessitates an opening through the water head for each bolt, which openings present a continuing possibility of leakage. Where a plurality of staybolts is utilized, each bolt having a shoulder thereon serving as a spacing means between the tube sheet and the water head, it not infrequently happens that the shoulders will not be effective in the proper planes. In such cases the tube sheet is necessarily initially deformed, by the mere act of tightening the staybolts, to an extent commensurate with inaccuracies either in the water head or in the shoulders on the bolts. This initial deformation is particularly objectionable since it has a tendency to loosen the connections between the tubes and the tube sheet. During operation, the unsupported portions of the tube sheet have a tendency to deform under the pressure conditions to which they are subjected, which, in many cases, will be well over 1,000 pounds to the square inch, thereby further tending

to loosen the joints referred to. In addition to this, the staybolts in projecting through the space in the water head, necessarily occupy part of the room therein and interfere with the desired flow conditions of the water.

In accordance with the present invention, the use of staybolts is entirely eliminated, whereby the water heads may be of any construction desired for the handling of the water regardless of the pressures transmitted to the tube sheets. This is accomplished by the utilization of reinforcing, stiffening or supporting skeletons cooperating with the tube sheet and holding the same against deformation, such skeletons preferably being positioned on the tube side of the tube sheet.

In the accompanying drawings there are shown, more or less diagrammatically, for purposes of illustration only, certain preferred embodiments of the present invention, it being understood that the drawings do not define the limits of our invention, as changes in the design of the apparatus, the construction and arrangement thereof, and in the particular construction of the tube sheets, may be made without departing either from the spirit of our invention or the scope of our broader claims.

In the drawings—

Figure 1 is a longitudinal sectional view through one form of heater constructed in accordance with the present invention;

Figure 2 is a view, partly in section and partly in elevation, along the line II—II of Figure 1 looking in the direction of the arrows; and

Figure 3 is a perspective view of a slightly modified form of tube sheet.

The heater illustrated in Figures 1 and 2 of the drawings comprises a shell 2 carrying at one end a tube sheet 3 and at the opposite end a pair of tube sheets 4 and 5. In this embodiment the tube sheet 3 constitutes a fixed head, and the sheets 4 and 5 floating heads.

The tube sheets are all provided with openings or perforations 6, as customary in the art, for the reception of tubes 7 extending continuously between the heads. In the particular embodiment illustrated, the tubes are arranged in four different nests A, B, C and D, providing a four-pass heater, the water flowing in the direction indicated by the

arrows *a*. The shell may be provided in known manner with one or more openings 8 for the admission of steam, and with one or more openings 8' for the withdrawal therefrom of condensate.

The tube sheet 3 cooperates with an annulus 9 constituting, in effect, a rim for the tube sheet, which may be connected thereto in any desired manner, as by bolting or welding, or it may merely abut thereagainst.

Extending diametrically of the tube sheet 3 in one direction is a rib 10 intersecting a substantially similar rib 11 extending diametrically of the tube sheet in the opposite direction. The rib 11 may be provided with oppositely extending flanges 12 adapted to be secured to the intermediate portion of the tube sheet in any desired manner, as, for example, by means of bolts 14. Intermediate ribs 15 of any desired number and arrangement may be provided.

The rim 9 may be provided in any desired manner with any desired number of laterally projecting studs 16 adapted to extend through the flange 17 of water head 18 and receive nuts 19 by means of which the water head is held in position. Preferably the rim 9 will be formed with an inwardly directed shoulder 20 adapted to abut against the tube 30 side of the tube sheet 3 and serve as a positive support therefor so that upon drawing home the nuts 19 the tube sheet will be rigidly clamped in position. It will be understood that the head may be formed with inwardly projecting partitions 21 dividing it into the desired spaces to obtain the multi-pass water flow referred to, one of these spaces having an inlet 22 for the water and another of the spaces having an outlet 23 leading therefrom.

In the preferred construction, the ribs 10 and 11 are formed integrally of the annulus 9 and the entire assembly is adapted to receive the tube sheet which is inserted into the recess defined in part by the inwardly directed shoulder 20. In this manner the assembly of the parts is facilitated and the desired strength given to the tube sheet by the mere act of thus inserting it into the annulus 50 and against the ribs.

Each of the tube sheets 4 and 5 may likewise be provided with reinforcing ribs 24 extending transversely thereof in one direction and with similar intersecting ribs 25 extending transversely thereof in the other direction, the ribs 24 and 25 constituting skeletons similar to that formed by the annulus 9 and the ribs 10, 11 and 15.

Also cooperating with each of the tube sheets 4 and 5 is a head 26, preferably bolted thereto in a manner similar to that described in connection with the head 18. If desired, the reinforcing ribs 24 and 25 may cooperate with a peripherally extending reinforcing rib 27, the presence or absence of such a rib

depending upon the construction of the heater.

Suitable pads 28 constituting a sliding support for the floating heads within the shell 2 may be provided, as is customary in the art, and a shell may carry a closure head 29 permitting access to and inspection of the floating heads.

If desired, the vapor space between the heads may be provided with any form of baffles 30 and held in position by suitable supports 31.

In operation, upon the admission of water to the interior of the water heads, the tube sheets are subjected to a considerable pressure tending to deform the tube sheets. This tendency toward deformation is effectively prevented, however, by the skeleton-like supports comprising beam-like means extending transversely of the tube sheets and upstanding from the general plane of the tube sheet body. This results in the provision of self-supporting tube sheets possessing the advantages referred to.

In Figure 3 of the drawings there is indicated, in perspective, a slightly modified form of tube sheet designed for use with either a single pass or a four-pass heater, depending upon the construction of the water boxes. The tube sheet is formed with openings 6' for the reception of the tubes and is shown cooperating with a skeleton-like frame F comprising an annulus 9' and intersecting ribs 10' and 11'. The ribs are shown as being bolted directly to the tube sheets, similar to the construction indicated in Figure 1 for the floating heads 4 and 5, and the tube sheet is illustrated as having studs 16' projecting therefrom for cooperation with a water head. The annulus 9' may be provided with any desired number of bosses 32 and openings 33 for the reception of bolts, by means of which it may be bolted directly to the periphery of the tube sheet. This figure illustrates a form of tube sheet adapted to constitute the floating head of a heater, as will be apparent to those skilled in the art.

Certain advantages of the present invention arise from the construction of what may be called a stayless heater providing unobstructed water spaces and self-supporting tube sheets. Such a construction obviates the possibility of deformation of the tube sheets either during the original installation or during use, and obviates the necessity of providing the water heads with openings such as have heretofore been necessary for the reception of the stays.

We claim:

1. In a heat exchanger, a supporting skeleton, and a tube sheet lying against and supported by said skeleton.
2. In a heat exchanger, a supporting skeleton comprising beam-like bracing means, and

- a tube sheet lying against and supported by said skeleton.
3. In a heat exchanger, a supporting skeleton comprising a rim and a transversely extending beam-like rib, and a tube sheet lying against and supported by said skeleton.
4. As an article of manufacture, a support-
- ing skeleton for tube sheets comprising a rim and a rib secured thereto, said rim being shaped for the insertion of a tube sheet. ¹⁰
- In testimony whereof we have hereunto set our hands.
